Primary Examiner — Cathron Brooks*Assistant Examiner* — Teddy Falloway(74) *Attorney, Agent, or Firm* — Gottlieb, Rackman & Reisman PC(57) **CLAIM**

The ornamental design for a device stand, as shown and described.

DESCRIPTION

FIG. 1 is a top plan view of my design;

FIG. 2 is a front view of the device stand thereof;

FIG. 3 is a right side view thereof;

FIG. 4 is a left side view thereof;

FIG. 5 is a rear view thereof;

FIG. 6 is a bottom plan view thereof; and,

FIG. 7 is a perspective view thereof, including showing support for a device (in broken lines).

The broken lines shown are included for the purpose of illustrating environmental structure and form no part of the claimed design.
